UNITED STATES PATENT OFFICE.

WILLIAM ASSHETON, OF BALTIMORE, MARYLAND.

WEB PRINTING AND WINDING MECHANISM.

Application filed March 16, 1923. Serial No. 625,454.

To all whom it may concern:

Be it known that WILLIAM ASSHETON, a citizen of the United States, residing at Baltimore, in the State of Maryland, has invented certain new and useful Improvements in Web Printing and Winding Mechanisms, of which the following is a specification.

This invention relates to an improved printing, cutting and winding machine and is especially designed to print upon a web of paper, allow the printing ink to dry, then trim or cut the web into proper widths and wind the printed and dried web into close rolls, thereby performing the several operations simultaneously on the same web and materially reducing the cost of production.

The machine is especially designed for printing sales-checks which are employed by merchants in making records of sales to various customers, but may be as readily used for making repeated impressions on a web for any purpose.

Heretofore, it has been the practice to print sales checks upon a web and wind the same into a loose roll but these operations are not satisfactory because the ink off-sets and further because the loose roll must be unwound and trimmed and the strip again wound into a close roll under tension in order that the required number of checks may be wound into a roll of small diameter ready for use in the machines or registers in which they are employed. This close rolling cannot be done while the ink is wet because of the large number of off-sets that result, consequently under the old practice it has been necessary to resort to separate trimming and winding operations after the ink has dried.

By means of my invention, I am able to carry on the several operations of printing, drying, trimming and winding the complete sales checks and thereby avoid the expense of the additional operations and the delay incident thereto.

The invention is illustrated in the accompanying drawings, wherein,—

Fig. 1. shows the improved machine in side elevation, as viewed from one side of the machine.

Fig. 2. illustrates the same also in side elevation but as viewed from the opposite side of the machine.

Fig. 3. shows the machine in top view.

Fig. 4. illustrates a vertical sectional detail through one end of the machine.

Fig. 5. shows the roll-winding end of the machine in end-elevation.

Fig. 6. illustrates the inking roll bearings in one side member of the frame as the same would appear if viewed on the line 6—6 of Fig. 3.

Fig. 7. shows a perspective detail of the frame sockets which carry the inking-roll bearings.

Fig. 8. illustrates one of the detached inking-rolls with its bearing block, and

Fig. 9. shows in a diagrammatic way the operations of printing plural checks side-by-side on a single web and the successive operations of producing folds in the printed web to allow the ink to dry and then placing the web under tension, trimming, cutting and then spooling the two rows of checks.

Referring to the drawing the numeral 10, designates two side frames of the machine which are sustained on a suitable base 11, and which extend vertically.

A horizontal shaft 12, extends crosswise between and has bearing in the two vertical side frames. For the purpose of the present invention this horizontal shaft 12, may be regarded as the driving shaft,—a pulley 13, being indicated on the end of the shaft for driving the same.

The shaft 12 carries a platen-roll 14, which is revolved as the shaft turns, and one end of this same shaft carries a gear 15 which latter meshes with and drives an idle pinion 16 on a short horizontal stub-shaft or stem 17 which projects from the side of the frame 10.

The pinion 16, meshes with and drives a gear 18, on a horizontal shaft 19 that extends crosswise of the machine with bearings in the two side frames, and the said shaft 19 carries a tension roll 20.

Above the shaft 19 the frames sustain another horizontal shaft 21, on which two spaced-apart circular heads 22 are carried, which latter are directly over the roll 20 and are designed to coat with the same in taking the web from the platen roll 14.

A gear 23 is provided on one end of the shaft 21 which gear meshes with and is driven by the gear 18, on the shaft 19, and a sprocket wheel 24 is provided on the opposite end of said shaft 21, for a purpose that will presently be explained.

The shafts 19 and 21 are carried in bear-

ing-boxes at the outer sides of the two frames 10 whereby the tension-roll 20 and heads 22 may be properly adjusted with respect to each other.

5 It will thus be understood that the tension roll 20 and heads 22 are driven from the gear 15 through the idler pinion 16.

Above the drive-shaft 12, there is provided a cylinder-shaft 25 which extends horizontally across the machine from one side frame to the other and this shaft is supported in removable bracket-bearings 26 which may readily be removed for a purpose presently to be explained.

15 One end of said upper shaft 25, carries a gear 27 which meshes with and is driven by the gear 15 on the shaft 12,—the gears 27 and 15 being of equal diameter and having the same number of teeth in order that a revolution of shaft 12 will cause a revolution of shaft 25.

The shaft 25 carries a printing cylinder 28, which may be attached thereto in any well-known manner, and this cylinder and 25 the platen-roll 14 are driven so each will complete a revolution at the same time.

Above the gear 27, which drives the printing cylinder, there is provided an idler gear 29, as shown in Fig. 1, of the drawing, which 30 idler meshes with and is driven by the gear 27 and said idler-gear 29 drives a gear 30 on the outer end of a horizontal shaft 31.

The shaft 31, extends all the way across 35 the machine and carries an ink-distributing roll 32, and on its far end, this shaft is provided with a grooved cam 33 in which a roller 34 on the end of a stationary arm 35 projects as shown in Figs. 2 and 3 of the drawings.

40 The shaft 31 is sustained in its opposite end-bearings so it may have a longitudinal movement therein, and as said shaft is revolved the stationary arm and the roller 34 thereon, by engaging the groove of cam 33, will cause said shaft to reciprocate longitudinally through its bearings and thus cause the ink roll 32 to reciprocate laterally as it revolves.

The roll 32, and other ink-distributing 50 rolls employed, and presently to be explained, are all carried in a specially designed bearing structure which will now be explained, reference being made particularly to Figs. 1, 4, 6 and 7 of the drawings.

55 Each side frame 10 has a curved bearing flange 36, and is also provided with a curved bearing-ledge 37 as best illustrated in Figs. 6 and 7 of the drawings. The bearing-flange has one bearing-recess 38 with a slot 39 at 60 one side thereof and a corresponding recess and slot is provided in the opposite side frame so that bearing-blocks 40, on the shaft 31, may fit said recesses 38 while the shaft itself may project through said slots 39 to the outer sides of the side frames.

Other bearing recesses 41, are provided in the flanges 36 for the reception of bearing-blocks 42 so that a plurality of shafts 43, 44, 45 and 46, may be mounted horizontally between said side frames whereby to sustain 70 rolls 47, 48, 49 and 50 respectively.

Between the roll 32, and the printing cylinder 28, two horizontal cross-shafts 51 and 52 are mounted in bearing-blocks 53 that are carried in bearing-recesses 54, in the ledge 75 37. These shafts 51 and 52 carry rolls 55 and 56, the circumferences of which latter rolls contact with the roll 32 and also with the printing-face of the cylinder 28.

On top of the two side frames 10 and extending horizontally, there is provided an ink receptacle 57 in which there is a horizontal ink-feeding roll 58. This ink roll 58 projects slightly through an opening in the rear of the ink-receptacle for a purpose that will 85 presently be explained.

One end of the shaft 59 on which the ink-feeding roll 58 is mounted, projects through an end-wall of the ink-receptacle and carries a ratchet-wheel 60 and a lever 61 is also 90 loosely mounted on the end of said shaft 59 and said lever carries a pawl 62 which engages said ratchet-wheel. The lever 61, hangs pendent from the outer end of the roll-shaft 59 and the lower end of said lever 95 normally lies in the path of a pin 63 that projects horizontally from a cam 64 on the end of shaft 25.

From the foregoing explanation it will be understood that as cam 64 revolves, the pin 100 63 will intermittently strike the lever 61 and swing the lower end laterally or to the right, as viewed in Fig. 1 of the drawing. This lateral swing of lever 61 causes the pawl 62 to engage the ratchet-wheel 60 and impart 105 a partial rotation to the latter and also to the shaft 59 and the ink-roll 58, so that upon each revolution of the cam 64, the ink-roll 58 will be given a partial rotation in the ink-receptacle.

Beneath the ink-receptacle 57, there is a horizontal rock-shaft 65, which has bearing in the two side-frames 10 and each end of this shaft carries an arm 66 at the inner side 110 of each frame, which arms extend upwardly and rearwardly with respect to the ink-receptacle. These arms 66 carry a horizontal roll 67 which latter has position between the ink-roll 58, and the roll 47, as best seen in Fig. 4 of the drawings, and in operation this roll 67 is designed to swing to and contact with the ink-roll 58 and then swing from said roll 58 and engage the roll 47 so as to 115 pick up ink from roll 58 and then transfer that ink to roll 47. The means for effecting this operation of the roll 67 is illustrated in Figs. 1, 3 and 4 of the drawings, and will 120 now be briefly described.

One end of the shaft 65, carries an arm 125 68, which latter depends at the outer side

of the side frame so that its lower end has position at the side of cam 64. A roller 69, is carried by the arm 68 and said roller engages and ridges on the face of the cam. 5 As the cam revolves, it swings the arm 68, a spring 70 serving to keep the roller 69 in engagement with the cam, and the arm rocks shaft 65, and swings the arms 66 and the roller 67. During this movement the 10 roller 67 is swung away from the ink roll 58 and into contact with the roll 47. As the cam continues to revolve the roll 67 swings back to the ink roll 58 and while it is in contact therewith said ink-roll is 15 given a partial turn by the operation of the pin 63 on the lever 61. In this way the roll 67 travels back and forth between the two rolls 58 and 47 and carries ink from the former to the latter. 20 A spring 71, keeps the lever 61 yieldingly pressed toward the path of the traveling pin 63.

Roll 47 is driven through its contact with the roll 32 which latter is positively driven 25 by the pinion 30 and ink is transferred from roll 47 to the roll 32.

The roll 32 is carried on the shaft 31 and this shaft also carries the grooved cam 33 on its outer end. Therefore, as shaft 31 30 revolves it is also given a longitudinal reciprocating movement because of the grooved cam 33 and the stationary arm 35 and roller 34. In this way roll 32 is reciprocated with respect to the rolls 47, 55, 35 56 and 48 with all of which it contacts as it revolves and the ink is therefore thoroughly distributed over the several rolls.

Roll 48 drives the rolls 49 and 50 respectively and transfers ink to the latter and 40 the roll 50 is provided for the purpose of supplying ink for a numbering drive, to which further reference will presently be made.

The several rolls 47, 32, 48, 49 and 50 45 are carried by the bearing-blocks 40 and 42 which latter are seated in the recesses 38 and 41 and after these blocks have been placed in their respective recesses a bar 72, is secured against the curved bearing-flange 50 36 and said bar has a retaining screw 73, for each bearing-block whereby it may be screwed against said block and hold the latter in place in its recess.

In a similar manner the blocks 53 for 55 shafts 51 and 52 are held in the recesses 54 by means of a bar 74 secured to the bearing-ledge 37 and retaining screws 75 engage each block.

The base 11, sustains a horizontal cross- 60 shaft 76, (shown in Fig. 4 of the drawing) on which a roll or web or paper 77 is mounted, and it is from this roll that the web is fed through the machine for printing, drying, trimming and final spooling into 65 complete rolls of sales-checks ready for the

registers which are used by the merchant.

From the roll 77 the web 78 is passed up over the platen-roll 14 and beneath the impression cylinder 28 which performs the printing operation. The web after being 70 printed passes between the roll 20 and the two spaced-apart heads 22 on the shaft 21. The heads 22 are so spaced as to engage the opposite marginal edges of the web at opposite sides of the printed area so 75 that the fresh ink will not be smeared by contact with any surface of a pulling roll.

After the web passes between the pulling roll 20 and heads 21 it is deflected downwardly by means of two spaced-apart heads 79 80 which are mounted on a cross-shaft 80 that is hung at each end in swinging bearing-bars 81. These bars (see Figs. 3 and 4 of the drawings) have their upper ends pivotally attached to the inner sides of the side frames 10, and their lower ends hang pendantly, while the cross-shaft 80 is carried by the bars between the upper and lower ends thereof.

Springs 82, are connected to the lower 90 ends of the bars 81 whereby to draw the latter toward the pulling-roll 20 so that the two heads 79 will have their circumferences engaging the marginal edges of the printed web and will direct the latter 95 downwardly. The shaft 80 and its two heads 79 are free to rotate and the freshly printed surface of the web is located between said heads 79 and out of contact with any surface which might blur the fresh ink.

After the printed web 78, passes the pulling devices 20-22 and 79-80 its printed surface is given an opportunity to dry by means which will now be explained, reference being made to Fig. 4 of the drawing.

Between the two side members of the base 11 and beneath the printing and pulling rolls, I provide a web-receiving receptacle 83. This receptacle is provided with an inclined partition-wall 84 which divides the receptacle into what may be termed a rear receiving trough 85, and a forward off-take receptacle 86. The inclined partition 84, is higher at the front than at its rear end and the lower rear end 87 terminates at a point spaced from or elevated with respect to the bottom 88,—the bottom however extending both forwardly and rearwardly with respect to said lower rear end 87 of the 110 inclined partition.

At the lower end of the inclined partition 84, there is provided a roller 89 which is merely mounted to rotate freely but is not positively driven.

As the printed web 78, travels downwardly from the pulling rolls it enters the trough 85 and, because of the inclined partition 84, is laid therein in a series of loose folds 90. A quantity of printed web is thus accumu- 125 130

lated in the trough when the machine is first started and prior to the feeding of the printed web from the trough to the tension and spooling devices which will presently be explained.

By allowing the printed web to accumulate in the trough 85, the printing ink thereon has time to sufficiently dry to prevent off-setting during the further operations thereon.

Above the off-take end 86 of the receptacle 83, a guide roller 91 is mounted, and the web from the trough 85, is fed beneath roll 89, then up from the off-take end 86 and around idle roller 91 which latter serves as a mere guide.

From the idle guide roller 91, the web extends upwardly and is passed over another guide roller 92 from which it then travels downwardly and passes around a series of tension rolls 93, 94, 95 and 96 respectively.

From the tension roll 96 the web is led to and passed around a second series of tension rollers 97, 98, 99 and 100 respectively as shown in broken lines in Fig. 1 of the drawing.

After leaving the tension roll 100, the web extends upwardly and passes around a guide roll 101 from which latter it is extended horizontally and passed between circular cutters 102 which are mounted in pairs on horizontal shafts 103, and 104 respectively.

The cutters 102 on shaft 103 and those on shaft 104 are so spaced as to trim the web to the proper width. In some instances I provide a pair of center cutters 105, as indicated by broken lines in Figs. 3 and 5 of the drawings, so that a web of sufficient width to receive two side-by-side impressions at one time from the impression cylinder 28 may be run through the machine and then severed by the center cutters 105, whereby two webs of complete sales-checks may be printed at one time as clearly indicated in the diagrammatic view shown in Fig. 9 of the drawings.

After the cutting, slitting or trimming operation by the cutters 102 and 105, the web passes between two guide rolls 106 and in case two rolls of sales-checks are being produced at once, one strip 107 is extended to and wound on a rod 108 while the other strip 109 is wound on the rod 110.

By reference to Figs. 2, 3 and 5 of the drawings, it will be noted that rod 108, has one end pivotally connected to a squared head 111, at the inner end of a short shaft 112 and that the outer end of said shaft carries a gear 113. The other end of the rod 108 is provided with a conical recess 114 into which the pointed end of a bearing screw 115, projects so as to permit the rod 108 to rotate. The bearing screw 115 extends

through the side frame of the machine and may quickly be withdrawn from engagement with the rod-recess whereupon the rod may be swung outwardly and a roll of sales-checks removed therefrom.

In precisely the same manner rod 109, has one end pivotally attached to one end of a short shaft 116 while its other end is held by a bearing-screw 117.

A gear 118, is carried on the outer end of the short shaft 116 and said latter gear meshes with and drives an idler gear 119 which latter drives the gear 113 on shaft 112.

Another idler gear 120, meshes with and drives the gear 118 while said latter gear is driven by another idler gear 121. A gear 122 on the outer end of cutter-shaft 104 drives the idler gear 121 and a gear 123 on the upper cutter-shaft 103, drives the gear 122.

The upper cutter-shaft 103 carries a clutch 124, which is actuated by a hand lever 125 while a sprocket-wheel 126 at the outer side of the clutch is driven by a chain 127 from the pulling roll shaft 21.

Normally the cutter-shaft 103, is being driven to revolve the cutters or trimmers 102 and 105 simultaneously with the operation of the printing cylinder 28 so that the printing, drying, trimming or cutting and spooling operations all take place at the same time on the web, but when a roll with the required number of completed sales-checks has been wound on either of the rods 108 or 109, the clutch lever 125 may be actuated to stop the winding long enough to permit the removal of the completed roll and the starting of a new roll.

Referring now to Figs. 1, 2, 3 and 4 of the drawings, (and particularly Fig. 3) a brief explanation of numbering devices employed on the machine will be made.

In printing sales-checks, it is common to number each check and I have therefore provided means on my machine for effecting this operation.

To this end, I provide a horizontal cross-shaft 128 whose outer end carries a gear 129 which meshes with and is driven by the gear 15.

The gear 128 is of the same diameter as that of the gears 15 and 27 so that all three gears and their shafts revolve at the same speed and begin and complete their revolutions simultaneously.

The shaft 128, carries a head 130, for each numbering device that is employed,—one if a single check is to be printed at a time on the web but two if the web is to receive two side-by-side impressions at a time. In the present instance two heads are presumed to be employed.

In printing sales checks it is common to provide a two part-check,—one part being

separated from the other by a score or perforated line to facilitate complete separation of a stub-part from the main check-part.

This means that each check-part should bear a number corresponding to the number on the other check-part.

With this object in view, I provide each head 130 with two numbering devices 131, both of which will revolve with the head and each device being set with the same number exposed for the first impression. Each numbering device has a trip pawl 132 by means of which its dials may be changed at each revolution.

15 In case two checks are to be printed at a time, I provide two numbering devices one of which has dials or discs bearing even numbers only while the other will have dials or disks bearing odd numbers only so that duplication of numbers will be avoided.

As shaft 128 and head or heads 130 is or are revolved the numbering devices 131 will be carried through a circular path and the numbering devices will contact with the 25 ink-carrying roll 50, and thereby be inked after which it will swing around until it is brought into contact with the web 78 at the number-impression station 133, shown in Fig. 4 of the drawing, whereupon the number will be printed upon the web.

After leaving the impression station the trip-pawl 132, will sweep over a stationary trip-lug 134 which is carried on one end of a bar 135 and the numbering device will thus 35 be advanced.

In this instance the numbering devices for each check are located diametrically opposite each other so that at each half-revolution of the shafts each half of a check will 40 be impressed with a like number.

This number operation at predetermined spaces on the web, in this instance, takes place before the web passes the printing cylinder and the operation thereafter upon the 45 web is as has been heretofore explained, and as can be readily understood by reference to the diagrammatic illustration of the complete operation on the web as shown in Fig. 9 of the drawings.

50 Having described my invention, I claim,—
1. In a web printing mechanism the combination with a printing cylinder, of means beyond the printing cylinder for piling the printed web in loose superposed folds to allow the ink thereon to dry sufficiently to prevent off-setting, means for drawing the web from the lowermost fold of the loose pile and placing said web under tension, means for trimming the web after it has 55 been placed under the latter tension and

means for spooling the web into a finished roll.

2. In a web printing mechanism the combination with a printing cylinder, of means for engaging opposite edges of the printed 65 web for drawing it from the cylinder, means for loosely receiving the printed web and arranging it in a series of superposed loose folds to retard its advance and allow the ink thereon to dry sufficiently to prevent 70 off-setting, means for drawing the web from the lowermost fold in the receiving-means and placing the said web under tension, means for trimming the printed web while it is under tension and means for winding 75 the trimmed web into a completed roll.

3. In a web-printing mechanism the combination with a printing cylinder of a receptacle having means for receiving the printed web and arranging the same in a 80 series of superposed folds one upon another said web extending from the lowermost fold from the receptacle, means for drawing said web from the receptacle and placing the same under tension and means for winding 85 the printed web into a completed printed roll.

4. In a web printing mechanism the combination with a printing cylinder of a receptacle beneath the cylinder and provided 90 with an inclined support to receive the printed web and arrange it in a series of folds over said inclined support, means for drawing the web from the lower end of the inclined support and placing the web under 95 tension and means for winding the printed web into completed rolls.

5. In a web printing mechanism the combination with a printing cylinder, of an inclined support onto which the printed web 100 is deposited and caused to assume a series of superposed loose folds,—the web extending from the lowermost fold beneath the inclined support, means beyond the inclined support for placing the web under tension 105 and means for winding the web while held under tension into a completed roll.

6. In a web printing mechanism the combination with a printing cylinder, of means for directing the printed web downwardly, 110 an inclined trough beneath the latter means to receive the printed web and cause it to assume a series of superposed loose folds, means at the bottom of said trough for directing the web from the lowermost fold 115 therein, means for placing the web under tension and means for spooling the web into a finished roll.

In testimony whereof I affix my signature.

WILLIAM ASSHETON.
